UNITED STATES PATENT OFFICE

145,122

DESIGN FOR A COMBINED PENCIL AND CALENDAR

Lawrence B. Crain, Los Angeles, Calif.

Application September 25, 1945, Serial No. 122,325

Term of patent 14 years

(Cl. D74—5)

To all whom it may concern:

Be it known that I, Lawrence B. Crain, a citizen of the United States of America and a resident of the city of Los Angeles, in the county of Los Angeles and State of California, have invented a new, original, and ornamental Design for a Combined Pencil and Calendar, of which the following is a specification, reference being had to the accompanying drawing, forming part thereof.

In the drawing:

Fig. 1 is a side elevational view of a combined pencil and calendar showing the essential fea-

tures of my new design in full lines, the numerals and printed matter appearing thereon being merely representative of that which would appear from time to time;

Fig. 2 is a side elevational view taken from a different angle to that disclosed in Fig. 1; and Fig. 3 is a top plan view thereof.

I claim:

The ornamental design for a combined pencil and calendar, substantially as shown and described.

LAWRENCE B. CRAIN.
